WINDOW SHADE BRACKET

Francis C. Jenkins, Wichita, Kans.

Application November 6, 1936, Serial No. 109,459

3 Claims. (Cl. 248—267)

My invention relates to improvements in window shade brackets and the object of my improvement is a window shade bracket of a neat and novel appearance, which can be easily applied.

In the drawing:

Figure I is the frame of window shade bracket; and

Figure II is a side view of window shade bracket, looking toward left side of window; and

Figure III is a diamond shaped shield of window shade bracket, containing slots for the blades to slip through; and

Figure IV is a side view of window shade bracket, looking toward right side of window; and

Figure V is a front view of window shade bracket when assembled; and

Figure VI is a top view of window shade bracket when assembled.

The frame 1, die cut, out of #14 gauge iron and containing a notch 2, and a hole 3, and bevel edged blades 4, is bent in a square U, so the points of the blades are even, across.

The blades are then slipped in slots 5, in diamond shaped shield 6, also die cut out of #14 gauge iron, to the stops 7. These slots are openings the same width and length, as the thickness and width of the blades.

The notch 2, in frame, is to receive the ratchet end of window shade roller. The hole 3, in frame is to receive the idle end of window shade roller.

The diamond shaped shield 6, being flush with

window casing, when window shade bracket is in position, receives the pressure of the "pull", when raising or lowering the window shade, and prevents the window shade bracket from working loose in the window casing.

The blades need not be longer than five-eighths of an inch, for ordinary household use.

The application of window shade bracket is very simple; by tapping or driving with a hammer on nose 8, as in driving a staple; until shield 6, is against window casing.

I claim:

1. A roller bracket having in combination a face plate with two perforations, and a U-strip with its ends penetrating said perforations and sharpened to enter a casing, a notch in one arm of said U-strip, and a circular aperture in the other arm.

2. A roller bracket having in combination a kite-shaped face plate with two parallel slits, and a U-strip with sharpened ends penetrating the slits, with shoulders stopped by said plate, and with a rectangular notch in one arm of said strip, and a circular aperture in the other arm.

3. A roller bracket consisting of two pieces of sheet metal, one of said pieces being a flat face-plate with two slits; and the other being a square-shouldered staple with tangs passing through the slits in said faceplate and sharpened symmetrically to a point, said strip having in its projecting portion a square cornered notch and a circular opening for a roller spindle.
